WIND MOTOR

Filed Dec. 22, 1927

UNITED STATES PATENT OFFICE

JULES D'ASSELER, OF GHENT, BELGIUM

WIND MOTOR

Application filed December 22, 1927, Serial No. 241,940, and in Belgium December 29, 1926.

The present invention relates to an improvement in wind-motors of the type where-in the vane wheel is equipped with rigid swivelling vanes which, on being acted upon by a regulating device by means of a sliding member mounted upon the wheel shaft, so turn as to escape the effect of too violent a wind, through modification of their angular position with respect to the general plane of the wheel.

In one of the recently known types of these machines, the rigid vanes carry, upon the extension of their transverse edge nearest the wheel centre, a swivel which is attached, by means of a flexible connection, to the external hoop which is the actual rim of a sliding member mounted upon the shaft and keyed upon it, whereby they jointly rotate, in such a manner that, whenever the regulating device acts upon the sliding member, the latter will, in its turn, and by means of the flexible connections, cause the vanes to alter their angular position with respect to the general plane of the wheel, to be afterwards caused to resume their initial position under cooperation of return springs, as soon as the traction effort has ceased.

According to the primary principle ruling the function of aero-motors of this description, the vane should get open so as to stand perpendicular to the plane of the vane wheel, failing which it cannot be possible to have the machine stopped neither to obtain a regular motion, it being even impossible to sufficiently protect the aero-motor against the destructive action of too violent winds, especially of wind gusts which are so detrimental to its existence.

Now, assuming the flexible connection to have been fastened to such a point of the sliding member rim as would, with respect to the general plane of the aero-motive wheel, lie in front of the point where the connection is attached to the pivot of the lower arm of the vane, the latter though acted upon by the

pull from the sliding member, can only be turned in an angle obviously smaller than 90°.

On the other hand, assuming the point whereat the cable is attached to the rim of the sliding member to be, for instance, shifted more to the right, so that the vane, acted upon by its connection under cooperation of the pull from the sliding member, will tend to open as much as 90°, not only will such an arrangement be difficult to carry out in the case of said connections being flexible (owing to the presence of the propping spokes of the wheel), the system will be, besides, liable to a great drawback in that, when the sliding member mounted upon the wheel shaft acts upon the vanes by means of the connections, these will, in turn, and owing to their being inclined to the direction of the sliding member, act upon this latter and impart it a pull sideways, viz. from left to right, and this results in considerable friction between the sliding member and its cotter, thus rendering the mechanism most defective.

The present invention is to eliminate these drawbacks in having each of the flexible connections passed over a pulley in such a manner that, from the pulley to the sliding member, the direction of its displacement will be parallel to that of the sliding member, so that this connection will exert upon the sliding member a pull in a direction parallel to that of the vane wheel shaft. As a result of this arrangement, any lateral effort exerted by the connections upon the peripheral rim of the sliding member, is avoided, as is likewise avoided any abnormal friction that would be exerted upon the cotter.

To facilitate comprehension of the principle and form of embodiment of this invention, the following description refers to the accompanying drawings, wherein:

Fig. 1 is a diagrammatic sectional view of a vane wheel, seen on line $x-y$ of Fig. 2, which is an approximately axial section

of the whole superstructure of an embodiment of the wind-motor lending itself to adaptation of connections and pulleys designed according to the invention.

- 5 The Fig. 1 shows, in full lines, the vane and the connection together with its pulley in the position they have on the sliding member arriving in its extreme position near the hub, and it shows, in dotted lines, the position taken by the vane and the connection on the sliding member reaching the opposite end of its stroke.

Considering the details of this Fig. 1, in the first mentioned position, the transverse edge 15 of the vane which is nearest the wheel centre takes a position *a*—*b* and the cable 21, starting from swivel *d*, passes between the ~~vane~~ propping spokes 2, it passes next over a pulley *e* fastened to a rim *k* mounted upon these 20 spokes 2 and ends on the peripheral rim 20 of the sliding member 22 mounted upon shaft 4 at a point situated near the wheel.

In the second mentioned position, the peripheral rim 20 of the sliding member 22 25 mounted upon the wheel shaft has shifted from *A*—*B* to *A'*—*B'*, the transverse edge of the vane has passed from points *a*—*b* to points *a'*—*b'* and swivel *d* has shifted on to *d'*, the vane being then entirely open. Thus 30 the vane has reached the position mentioned without exerting any sideward pull upon the sliding member 22, the length of the cables 21 as from pulleys *e* acting only in the direction of the wheel shaft.

35 Referring to Fig. 2, the vane wheel comprises a plurality of vanes 30 pivotally mounted upon spokes 1 which are perpendicular to the wheel shaft 4. The spokes 1 which carry the vanes are fastened to a 40 flange 2' being part of the hub 3 which is keyed upon the inclined shaft 4 whereby the wheel is carried.

In the embodiment shown in Fig. 2, the rigid vanes 30 are subdivided by the spokes 45 1 into two portions of different area; it should, however, be borne in mind that the invention could as well be applied to an aero-motor equipped with movable rigid vanes of another design, namely with vanes divided 50 into two portions of equal area by their swivelling axis which is that of the spoke, or with vanes entirely mounted at one side of a radial arm.

55 In the embodiment of the aero-motor shown in Fig. 2, the swivelling of the vanes caused by traction upon the cables 21 is due to the power of a centrifugal governor 16 acted upon by the rotary speed imparted to the vane wheel by the wind; it should, however, 60 be observed that the invention could be applied as well to an aero-motor wherein the swivelling of the vanes, which is here due to traction under cooperation of flexible connections and of the sliding member mounted 65 upon the wheel shaft, would be effected

through any regulating arrangement other than the centrifugal governor shown in the present drawings. This centrifugal governor 16 is connected to the sliding member 22 by means of any appropriate transmitting mechanism, by such as for instance the crank lever 24 engaging rods parallel to the respective shafts of the vane wheel and governor and connected to nonrotary collars engaging respectively the sliding member 22 and the sliding element of the governor 16. Upon decrease of the speed of rotation the vanes 30 are returned to working position under action of coil springs 26 connected to the side edge of vane 30 and the free end of the rigid bar 25 which is positioned in front of the general plane of the vane wheel.

70 It is to be noted that this invention, to be carried into practice with all of the advantages that can derive from it requires the employment of very flexible connections capable of easily passing on the pulleys, subject to no abnormal friction.

75 I claim:

1. In a wind-motor of the type herein set forth, a vane wheel adapted to rotate under the action of the wind and having the vanes pivotally mounted thereon, a member adapted to rotate with the vane wheel and to slide in a direction at right angles to the plane of rotation, the position of said member being controlled by the speed of rotation of the vane wheel, flexible connections between each vane and said member, guide pulleys for said flexible connections revolving with the vane wheel and supported directly forward of the point of attachment of the flexible connections to said member and elastic means to return the vanes to working position upon decrease of the speed of rotation.

80 2. In a wind-motor of the type herein set forth, a vane wheel adapted to rotate under the action of the wind and having the vanes pivotally mounted thereon, a member adapted to rotate with the vane wheel and to slide in a direction at right angles to the plane of rotation, the position of said member being controlled by the speed of rotation of the vane wheel, flexible links between each vane and said member, guide pulleys for said flexible links revolving with the vane wheel and so positioned that the portion of each flexible link extending between a guide pulley and said member is always parallel to the direction of the sliding movement of the latter, whatever be the position of the vanes.

85 3. In a wind-motor of the type herein set forth, a vane wheel adapted to rotate under the action of the wind and having the vanes pivotally mounted on spokes radially projecting from the hub thereof, propping spokes inclined to and connecting the outer end of said radial spokes to the hub, a mem-
